United States Patent Office

Des. 229,980

Patented Jan. 15, 1974

229,980

CARD FILE

Moritoshi Kimura, 34-7, 2-chome, Higashi Mukojima,
Sumida-ku, Tokyo, Japan

Filed Apr. 27, 1971, Ser. No. 138,008

Claims priority, application Japan Dec. 31, 1970

Term of patent 14 years

Int. Cl. D19—02

U.S. Cl. D74—2 A

FIG. 1

FIG. 2

FIG. 3

FIG. 4

FIG. 5

FIG. 1 is a plan view of a card file showing my design;
 FIG. 2 is a front view thereof, the rear being a mirror image of the front shown;

FIG. 3 is a bottom view thereof;

FIG. 4 is a left side elevation thereof, the right side being the same as the left side shown; and

FIG. 5 is a perspective view thereof.

I claim:

The ornamental design for a card file, as shown and described.
